UNITED STATES PATENT OFFICE.

MORGAN BROWN, OF LIFSEY, GEORGIA.

BUGGY-TOP RAISER.

SPECIFICATION forming part of Letters Patent No. 705,901, dated July 29, 1902.

Application filed November 12, 1901. Serial No. 82,004. (No model.)

To all whom it may concern:

Be it known that I, MORGAN BROWN, a citizen of the United States, residing at Lifsey, in the county of Pike, State of Georgia, have 5 invented certain new and useful Improvements in Buggy-Top Raisers; and I do hereby declare the following to be a full, clear, and exact description of the invention, such as will enable others skilled in the art to which 10 it appertains to make and use the same.

This invention relates to tops for vehicles, and particularly to means for raising and lowering them without the occupant of the vehicle changing his position therein and which, 15 furthermore, will enable a person to raise and lower the top from the exterior of the vehicle and at either side thereof.

A further object of the invention is to provide a construction which may be easily and 20 quickly applied to and removed from a vehicle-top and in the operation of which the final movements will be retarded to prevent jolting.

Other objects and advantages of the invention 25 will be understood from the following description.

In the drawings forming a portion of this specification, and in which like numerals of reference indicate similar parts in the several 30 views, Figure 1 is a side elevation showing a buggy-top with the present invention applied thereto, the position of the lever and the connected brace when the lever is raised being indicated in dotted lines. Fig. 2 is a top plan view of the double rock-lever with the back braces of the top connected thereto. Fig. 3 is an enlarged elevation showing the manner 35 of clamping the back braces to the rock-lever. Fig. 4 is a section on line 4 4 of Fig. 2 and 40 showing the manner of connecting the helical springs.

Referring now to the drawings, there is shown a buggy comprising the box 5 and the seat 6 and connected to which seat, at the forward portions thereof and at each side, is a bracket 7, to which are pivoted the upwardly-diverging braces 8, 9, and 10, connected at their upper ends to the top-frame in the usual manner and having the usual knuckle-braces 45 between them.

Pivotedly connected with the top-frame at each side of the top and at the upper end of the brace 9 is the upper member 12 of a knuckle-brace, including also the lower member 13, the brace being adapted to be broken by 55 movement thereof rearwardly.

Instead of pivoting the lower ends of the members 13 to brackets connected to the seat 6 they are connected with a double rock-lever. This rock-lever consists of a central portion 60 or shaft 14, mounted for oscillation in bearings 15 and 16, which are secured to the rear portion of the vehicle-seat, and at the ends of the shaft are the handle portions 17 and 18, which extend forwardly at right angles to the 65 shaft and project with their free ends beyond the front edge of the vehicle-seat, so that the shaft may be rocked and both handles raised or lowered by manipulation of a single handle.

The members 13 are connected rigidly to the 70 handle portions adjacent to the shaft by means of clamps 19, each comprising two plates having registering channels. The plates are adjusted at opposite sides of the brace and handle to be connected, and a bolt 20 is engaged 75 therewith to hold them securely in place and clamp the members rigidly together. Then if either handle be moved the other handle will be similarly moved through the medium of the connecting-shaft, and the members 13 80 at both sides will be correspondingly operated. If the handles be raised, the knuckle-brace will be broken and the top moved backwardly and lowered, while if the handles be then moved in the opposite direction the top will 85 be raised until the knuckle-brace is again straight.

To prevent jarring of the structure at the limits of movement of the top, helical springs 22 and 23 are provided and are disposed to 90 encircle the shaft, the inner ends of the springs being engaged by the heads of the bolts 24, which hold the bearing-boxes in place, while the outer ends of the springs are engaged beneath the heads of the bolts 20. 95 At both limits of movement of the rock-lever the spring is under tension at each end of the shaft.

In practice modifications of the specific construction shown may be made and any suit- 100

able materials and proportions may be used for the various parts without departing from the spirit of the invention.

What is claimed is—

- 5 The combination with a vehicle-top and the rear knuckle-braces thereof, of a rock-shaft, handles, clamps each comprising two plates having converging channels and a clamping-bolt engaged through the plates said plates
10 being disposed with their corresponding channels in registration, with a knuckle-brace and a handle therein respectively, bearings for

the shaft secured to the vehicle and comprising movable members and bolts for holding them in position, and helical springs wound upon the shaft and each having its ends respectively clamped beneath the heads of the bolts of the clamps and bearings. 15

In testimony whereof I affix my signature in presence of two witnesses.

MORGAN BROWN.
